BERTHA EHRLMAN, SARA JOHANSON, CLAUS M. JOHANSON, AND PALMER M. PETERSON, OF TACOMA, WASHINGTON.

CLAMP FOR IRONING-BOARD CLOTHS.

1,420,027.

Specification of Letters Patent. Patented June 20, 1922.

Application filed November 25, 1921. Serial No. 517,609.

To all whom it may concern:

Be it known that we, BERTHA EHRLMAN, SARA JOHANSON, CLAUS M. JOHANSON, and PALMER M. PETERSON, citizens of the United States, and residents of the city of Tacoma, county of Pierce, State of Washington, have invented certain new and useful Improvements in Clamps for Ironing-Board Cloths, of which the following is a specification.

This invention relates to improvements in cloth holding clamps for ironing boards, or the like, and more particularly to adjustably extendable clamps adapted for the purpose of securing a covering or cloth over the surface of an ironing board.

The principal object of the present invention is to provide clamps of the above described character that may be easily and quickly applied or removed, which are simple in construction and in the manner of their use, and can be provided at a relatively small cost.

It is also an object of the invention to provide such a clamp comprising a pair of hook holding plates which are fixed to the opposite ends of a tensioning member, such as a coiled spring, and which have means provided thereon to which clamping hooks, also provided, may be removably and adjustably secured; said hooks being formed with hooked end portions that are adapted to engage a cloth at opposite edges of an ironing board and thereby hold the cloth tightly across the top of the board and properly in place.

Other objects of the invention reside in the details of construction of the various parts of the clamp and in their combination and use.

In accomplishing these and other objects of the invention, we have provided the improved details of construction, the preferred forms of which are illustrated in the accompanying drawings, wherein—

Fig. 1 is a perspective view of a cloth holding clamp constructed according to the present invention.

Fig. 2 is an underside view of an ironing board to which clamps embodied by the present invention have been applied.

Fig. 3 is an enlarged cross-sectional view

of a board with cloth and clamp applied thereto.

Referring more in detail to the drawings—

1 designates an ironing board, which may be of the usual type, wider at one end than at its opposite end and provided with a covering or cloth 2 which is drawn taut across the top thereof and extended about and beneath its opposite side edges.

Since it is undesirable to permanently secure such cloths to the board, because they frequently need to be replaced, we have provided the present type of clamp for holding the cloth removably upon the board.

The preferred type of clamp, as illustrated in Fig. 1, comprises two elongated metal plates 3 and 3' which are secured by means of back-turned tongues 4, at their ends, to the opposite ends of a coiled spring 5. Each of the plates has a plurality of hooks 6 stamped downwardly from its body portion, whereby clamping hooks 7 and 7' are removably and adjustably fixed to the plates.

Each of the hooks 7 consists of a single piece of stiff wire bent to form two spaced apart fingers 8 and 8' and a connecting portion 9 at their inner ends having an offset portion 10 wherein the hooks 6 are seated. The outer ends of the fingers have laterally turned hook portions 11 with slightly in-turned ends 12 which are adapted to engage the edge of the board and to be clamped thereagainst by the tension of the spring to hold the edges of the cloth, which have been drawn over and about the edges of the board.

When using clamps of the above character, the cloth is first applied to the board, as shown in Figures 2 and 3, and the clamps applied across the under side of the board with the ends of the hook members 7 seated over the opposite edges of the board, as is shown in Figure 3, with the slightly in-turned ends 12 engaging the cloth to prevent any possible slippage of the cloth or of the clamp from position. By adjusting the hooks 7-7' to engage the proper hooks 6 of the plates 3 the desired tension may be placed on the hooks 7, thereby adapting the

devices for use on either the large or narrow ends of the board or on boards of various widths.

One of the principal advantages of the present clamp is that it permits the use of material for covering the board which otherwise would not be of sufficient strength. This is due to the fact that the ends of the hooks 7 extend over the edges of the board and grip the cloth there instead of being hooked into the cloth as is now usually done.

It is readily apparent that various changes in the character of the hooks 7 used and in the manner of attaching them to the plates 15 3, could be made without departing in any way from the spirit of the invention, and for this reason we do not wish to be limited only to the details of construction shown.

Having thus described our invention, what 20 we claim as new therein and desire to secure by Letters-Patent, is:

1. A cloth holding clamp for ironing boards comprising, a tensioning spring, plates fixed to the opposite ends of said 25 spring and hooks, for engaging the opposite edges of a board, secured detachably to said plates.

2. A cloth holding clamp for ironing boards comprising a tensioning spring, plates 30 having their inner ends secured to the opposite ends of said spring, and hook mem-

bers secured adjustably and removably to the said plates for engaging the opposite edges of a board to which they are applied.

3. A cloth holding clamp for ironing 35 boards comprising a tensioning spring, elongated plates having their inner ends secured to the opposite ends of the said spring; said plates having hooks formed thereon at intervals longitudinally thereof and cloth holding hooks, for engaging opposite edges of a board to which the device is applied, applicable selectively to the hooks of said plates to adapt the device to boards of different widths.

4. In a device of the class described, the combination with a tensioning spring and hooks for engaging the opposite edges of a board to which the device is applied, of adjusting plates having their inner ends 50 secured to the opposite ends of the said spring and having anchor members formed thereon to which said hooks may be selectively applied to adapt the device to boards of various widths.

Signed at Seattle, Washington this 16th day of November 1921.

BERTHA EHRMAN.
